UNITED STATES PATENT OFFICE.

WILLIAM PRICE ABELL, OF DERBY, ENGLAND.

BABY FURNITURE.

SPECIFICATION forming part of Letters Patent No. 700,001, dated May 13, 1902.

Application filed February 6, 1901. Serial No. 46,254. (No model.)

To all whom it may concern:

Be it known that I, WILLIAM PRICE ABELL, a subject of the King of Great Britain, residing at Castle Hill, Derby, England, have 5 invented certain new and useful Improvements in Baby Furniture, of which the following is a full and complete specification, such as will enable those skilled in the art to which it appertains to make and use the 10 same.

The object of this invention is to provide means for preventing infants from getting into mischief, while at the same time allowing them freedom of movement and amusement and free exercise for the full development of their limbs, chest, and muscles; and with this and other objects in view the invention consists in a device for the purpose specified constructed as hereinafter described and 20 claimed.

To attain the object of my invention, I provide a portable and collapsible pen or inclosure device consisting of a plurality of parts, panels, or sections, which are preferably four 25 in number, two of the adjacent parts, panels, or sections being of the same length and shorter than the other two, which are also of the same length, the said parts, panels, or sections being connected at the ends, so as to 30 allow them to swing or turn freely one upon another, and I place this device on the ground either out of doors or in a room, having preferably first spread a rug beneath the same larger than the pen or inclosure device, and 35 on this rug I place the said device, and the baby or child is placed therein.

In the drawings forming part of this specification, in which the separate parts of my improvement are designated by the same 40 reference characters in each of the views, Figure 1 is a side elevation of my improved pen or inclosure device; Fig. 2, a plan view thereof, and Fig. 3 an end elevation showing the pen or inclosure device folded or collapsed.

In the practice of my invention I provide a pen or inclosure device, which in the form of construction shown in the drawings is composed of four panels, parts, or sections a' , a^2 , 45 a^3 , and a^4 , and these parts, panels, or sec-

tions are hinged together at the ends or so connected as to allow them to freely turn one upon another. Two of these parts, panels, or sections a^2 and a^3 are made shorter than the remaining parts, panels, or sections a' and a^4 , 55 so as to enable the pen or inclosure device to be folded, as shown in Fig. 3.

The separate parts, panels, or sections are preferably composed of laths or bars A, B, and C, which are about three inches apart, 60 and are so connected with posts E and E' as to freely turn thereon, the said laths or bars being preferably threaded onto the said posts. By making the two parts, panels, or sections a^2 and a^3 shorter than the other two 65 and connecting them in the manner described at E' the connection at E' may be folded inwardly, so that the parts of the pen or inclosure device will assume the position shown in Fig. 3. 70

In ordinary use the pen or inclosure device is placed on the ground or on the floor, as shown in Fig. 2, and when not in use and for shipping and other purposes the separate parts thereof are folded, as shown in Fig. 3, 75 and may be more compactly folded than is shown in said figure.

Having thus fully described my invention, what I claim as new, and desire to secure by Letters Patent, is— 80

A pen or inclosure device of the class specified consisting of four separate parts, panels or sections, two of which are hinged together and are shorter than the other two and are of the same length, the other two being also 85 hinged together and hinged to the first two and being also of the same length, each of said parts or sections being composed of separate parts or strips connected with the corner-posts so as to turn thereon, four of said 90 posts being employed, substantially as shown and described.

In testimony that I claim the foregoing as my invention I have signed my name, in presence of the subscribing witnesses, this 95 24th day of January, 1901.

WILLIAM PRICE ABELL.
